(57) **CLAIM**

The ornamental design for a shoulder strap for bag and/or carrier, as shown and described.

DESCRIPTION

FIG. 1 is a front view of a shoulder strap showing the new design;

FIG. 2 is a rear view thereof;

FIG. 3 is a top view thereof;

FIG. 4 is a bottom view thereof;

FIG. 5 is an enlarged right side view thereof; and,

FIG. 6 is an enlarged left side view thereof.

The broken lines and the relatively light deemphasized portions within depict portions of the shoulder strap for bag and/or carrier which form no part of the claimed design.
